UNITED STATES PATENT OFFICE.

WALTER THOMAS SYKES, OF PHILADELPHIA, PENNSYLVANIA, ASSIGNOR TO
THE PHILADELPHIA TEXTILE MACHINERY COMPANY, OF SAME PLACE.

CONDENSER OR FINISHER CARDING-MACHINE.

SPECIFICATION forming part of Letters Patent No. 508,064, dated November 7, 1893.

Application filed May 17, 1893. Serial No. 474,507. (No model.)

To all whom it may concern:

Be it known that I, WALTER THOMAS SYKES, a citizen of the United States, residing at the city of Philadelphia, in the county of Philadelphia and State of Pennsylvania, have invented certain new and useful Improvements in Condenser or Finisher Carding-Machines, of which the following is a specification.

My invention has relation to condenser or finisher carding engines or machines; and it relates more particularly to the construction and arrangement of the doffer-rolls thereof.

Hitherto the rolls constituting the ring-doffers of carding machines or engines have generally been provided with detachable rings formed of leather or the like having wire staples inserted through the same and disposed at an angle to the surface thereof and such rings mounted on the roll or cylinder at suitable distances apart, but the main objections to such rings have been, that they required constant stripping for removing accumulating extraneous matter from about the prongs or wires constituting the clothing thereof, which not only tended to disarrange the operative positions of the same for effective action, but also in a short time rendered it necessary to remove the ring-doffers from the rolls or cylinders of the machine in order to replace the same with new rings. Moreover, such rings in use very imperfectly straightened or combed out the entangled fibrous material in its passage from the carding cylinder anterior to being formed into sliver and its release from the rub-rolls or aprons of the condenser or finisher for permitting of the spinning thereof. Then such rings when fastened or tacked to the surfaces of rolls or cylinders of wood or the like, in practice presented further objections, among which may be mentioned the warping and stretching of the leather as well as the breaking away of the wires or prongs constituting the clothing thereof, along unprotected portions of the bands or strips, necessitating thereby frequent stoppages of the machines for removal of the rings for repairs or replacement of the rolls or cylinders with new bands or rings.

The principal objects of my invention are

50 first, to provide a simple, durable, comparatively inexpensive and efficient doffer-roll,

comprising a roll or cylinder provided with a series of closely arranged parallel grooves in the body thereof arranged in groups and into which grooves to constitute each of the rings 55 of the roll or cylinder so formed are inserted and calked narrow fillets or strips of metal having saw-toothed edges projecting therefrom and with intervening plain or smooth surfaces between companion integral saw-toothed rings of the roll or cylinder and the respective teeth of the closely arranged parallel metal strips or fillets of each ring occupying staggered or break joint positions with respect to each other in each ring of the series integrally formed in the body of the roll or cylinder and projecting therefrom, the construction and arrangement being such that fibrous material treated thereby is appreciably enhanced in quality and value; second, to provide a roll 60 or cylinder with a series of grooves arranged parallel to the ends of the roll or cylinder in groups and into each of the parallel grooves of the series of groups is inserted a fillet or strip of metal having a saw-toothed edge projecting from the surface of the roll or cylinder and intervening smooth surfaces between the series of such toothed integral rings of the roll or cylinder and the teeth of each staggered with respect to the others and the interior of the cylinder provided with a steam or heating coil for warming the roll or cylinder, in order to enable moist or wet material in its passage from the carding cylinder to such roll or cylinder to be so treated as to enhance 65 the character of the product through the thorough combing or straightening out of the same in parallel threads or courses prior to its delivery to rub-rolls or aprons for forming into sliver; third, to provide a doffer-roll composed of a series of integral saw-toothed rings 70 formed of narrow strips or fillets of metal closely arranged in parallel courses in contradistinction to being wound spirally around the roll or cylinder and with intervening 75 smooth or plain surfaces or spaces provided between each of the series of saw-toothed rings constituting the doffer roll or cylinder for straightening or combing out with uniformity and for enhancing the character of 80 the fibrous material so treated prior to its delivery to rub rolls or aprons for further treat- 85

ment thereby and preparatory to the spinning thereof; fourth, to provide a doffer-roll for a condenser carding engine or machine with integrally formed rings arranged around the periphery thereof and with the teeth of each ring projecting therefrom in closely arranged parallel courses and with intervening smooth surfaced spaces between the series of companion toothed rings and the respective teeth thereof arranged in such manner as to present a staggered position with respect to each other for enabling in the use of the same fibrous material issuing from the carding cylinder to be taken up by the teeth of each of the series of rings of the roll or cylinder and thoroughly combed or straightened out into parallel or analogous courses and with extraneous matter removed therefrom preparatory to the formation of the same into sliver or the like and before delivery to sub rolls or aprons for forming into rovings; and fifth, to provide an expeditious and economical method for forming such a doffer-roll or cylinder with a series of integral saw-toothed rings and with intervening smooth surfaced spaces between companion integral saw-toothed rings disposed along the periphery thereof.

My invention consists of a doffer-roll for a condenser or finisher carding engine or machine, provided with integral metal saw-toothed grouped rings arranged at suitable distances apart and with intervening smooth surfaced spaces between companion saw-toothed integral grouped rings arranged along the periphery thereof and the teeth of each of the saw-toothed rings of the series of grouped rings occupying staggered positions with respect to each other.

My invention further consists of a doffer-roll for a carding machine, comprising a hollow cylinder provided with an internal coil for heating or warming the surface thereof and the cylinder provided with a series of integral saw-toothed rings each composed of strips or fillets of metal having a saw-toothed edge set into closely arranged parallel grooves in groups formed in the body of the cylinder and made integral therewith by being calked or otherwise secured thereto and intervening smooth surfaced spaces between the respective integral saw-toothed rings arranged along the periphery of the cylinder, the construction and arrangement being such, as to thoroughly or efficiently straighten or comb out and strip the fibrous material in passing from the carding cylinder to the rub-rolls or aprons by forming the same into regular or uniform strips, or slivers preparatory to the spinning thereof.

My invention further consists of a doffer-roll, comprising a series of integral metal saw-toothed rings each provided with closely arranged parallel courses of exposed saw-toothed strips or fillets of metal set into grooves formed in the body of the roll or cylinder and intervening smooth surfaced spaces between companion saw-toothed rings of the

series constituting the doffer-roll or cylinder and calked or otherwise secured thereto.

My invention further comprises the method of making a doffer roll or cylinder for a carding machine, which consists in providing a roll or cylinder with grooves in closely arranged parallel courses with respect to the end of the roll or cylinder and with intervening smooth surfaces between each group of grooves to constitute each integral ring between the intervening smooth surfaced spaces of the roll or cylinder, cutting, finishing or shaping teeth along one edge of a strip or fillet of metal and presenting under pressure the strip or fillet to and inserting into the series or groups of closely arranged parallel grooves of the cylinder to form a series of integral saw-toothed rings and calking each inserted group of saw-toothed strips or fillets to constitute one of the series of rings of the roll or cylinder to position.

My invention further comprises the method of forming a doffer-roll or cylinder by providing closely arranged parallel grooves in groups and intervening smooth surfaced spaces between the series of groups of parallel grooves, forming in regular sequence along the edge of a strip or fillet of metal saw-teeth and conveying and presenting the strip or fillet to and securing the same into the groups of grooves and calking the inserted saw toothed strips or fillets into the groups of grooves of the roll or cylinder with the teeth arranged in close parallel courses of each ring of the series comprising the roll or cylinder occupying a flaring staggered position with respect to each other for effectually combing, straightening out and improving the character or quality of fibrous material conducted from the carding cylinder for treatment thereby and preparatory to its delivery to rub-rolls or aprons as sliver for forming into skeins or ribbons, for permitting the spinning of the same.

My invention further consists of a doffer-roll for a carding machine, comprising a cylinder provided with integral metal saw-toothed rings arranged at suitable distances apart and calked thereto and with smooth intervening surfaced spaces between each of the rings of the series constituting the roll or cylinder; and my invention further consists of the improvements in metal doffer-rolls for carding engines or machines provided with integral saw-toothed metal rings having intervening smooth surfaced spaces between each of the rings thereof such as hereinafter described and claimed.

The nature and scope of my invention will be more fully understood from the following description taken in connection with the accompanying drawings forming part hereof, in which—

Figure 1, is a perspective view showing the mode of producing a doffer-roll according to my invention; and Fig. 2, is a view of a doffer-roll, comprising a hollow cylinder with a

steam or heat conducting coil mounted therein and provided with integral metallic saw-toothed rings arranged at suitable distances apart along the periphery thereof, for enabling 5 moist fibrous material to be worked thereby for improving the quality or character of the resultant fibrous product obtained therefrom.

Referring to the drawings *a*, is a supported reel upon which is coiled a narrow strip or 10 fillet of metal *a'*, which is led therefrom over a grooved pulley *b*, pivotally supported to a bracket *b'*, which is attached to a base-plate 15 *a²*. The strip or fillet of metal *a'*, from the pulley *b*, passes through a guide *c*, to a rotating cutter *d*, which is mounted on a horizontal shaft *d'*, journaled in standards *d²* and *d³*. The cutter *d*, is actuated in such manner as to form in regular sequence **V** or similar shaped teeth along one of the edges of the strip 20 or fillet *a'*. Upon the shaft *d'*, is mounted a pulley *d⁴*, driven through the intervention of a belt *d⁵*, by any suitable power, not shown. On the base-plate *a²*, is supported an adjustable guide-block *a³* provided with a vertically- 25 disposed die *a⁶*, and upon the surface of which die rests the strip or fillet of metal *a'*, during the formation of the saw-teeth in regular sequence along one edge thereof by means of the rotating cutter *d*, and during the travel 30 of the same therefrom.

a⁷, is a spring tongue seated to the standard *d²*, and tending to maintain the strip or fillet *a'*, firmly resting against the die *a⁶*, in contact with the rotating cutter *d*, in order to 35 insure uniformity in the depth of the teeth formed in the strip or fillet *a'*. This strip or fillet of metal *a'*, after having the teeth formed in one edge thereof passes between pressure rolls *f* and *f'*, adjustably connected with a 40 standard *f²*, mounted on the base plate *a²*, and from which pressure rolls the same passes to a reel *g*, mounted on a shaft *g'*, which is supported in any suitable manner and from which reel the saw-toothed strip or fillet *a'*, is conducted to and through a second series of 45 pressure rolls *h* and *h'*, mounted on shafts *h²* and *h³*, which are supported in standards *h⁴* and *h⁵*. The roll *h*, is provided with a lever *h⁷*, for controlling the degree of pressure exerted upon the metal strip or fillet *a'*, in its 50 passage under tension between the rolls *h* and *h'*.

h⁸, is a channeled plate provided with an adjustable grooved guide pulley *h⁹*, which is 55 journaled to an adjustable bifurcated arm *h¹⁰*, thereby affording the means for permitting of the insertion of the saw toothed strip or fillet of metal *a'*, face to the pulley *h⁹*, into the required position in the grooves *c'*, of the 60 cylinder *C*, to comprise in its finished condition the doffer-roll or cylinder for a condenser, finisher or other carding engine or machine. The grooves or recesses *c'*, in the surface of the cylinder *C*, are formed in a lathe or other 65 suitable appliance in any preferred manner. The toothed fillet or strip of metal *a'*, guided and automatically secured or calked into the

groups of grooves or recesses *c'*, formed in the body of the roll or cylinder in closely arranged parallel courses with respect to the 70 ends of the cylinder or tube *C*, form projecting saw toothed metallic rings which are arranged at suitable distances apart thereon and the teeth of each of the rings constituting the roll or cylinder arranged in parallel 75 rows occupy staggered or break joint positions with respect to each other in the series of closely arranged parallel courses of each ring.

In Fig. 2, is illustrated a hollow cylinder *C*, 80 provided with end journals *i*, having a collar *i'*, mounted thereon and abutting against the end or head *c²*, at each end thereof. *j*, is a pipe passing through the journal *i*, and formed into coils *j²*, in the interior of the cylinder *C*, 85 for the passage therethrough of steam or other suitable heating medium for warming the roll or cylinder. The end of the coiled pipe *j²*, is connected with the pipe *j*, by means of a two-part coupling device *j³*, as fully illustrated in Fig. 2, or in any other preferred manner and the end of the pipe *i*, is coupled to a heat supply, not shown, but which will be readily understood, whereby under due regulation the surface of the cylinder is maintained in a more or less heated condition for 90 purposes to be hereinafter explained.

In some instances the fibrous material to undergo treatment requires a mild heat to 95 successfully work and give as a resultant product by such treatment of the doffer-rolls, a superior sliver for subsequent use. Moreover, the coarse or more common fibrous materials, such for example as are used in the 100 making of a low grade of carpet fabrics, required to be treated by such machines as hereinbefore described, are at certain seasons presented thereto for being worked in a more or less moist or wet state, and in such condition it is very difficult to satisfactorily work 105 the same, and hence considerable waste even with undue care exercised, will accumulate. Practice has also demonstrated that such 110 fibrous materials as require treatment in carding engines or machines, are affected by 115 changes of temperature, and in such manner as to cause the material to become rampant or wild, and consequently it is a source of 120 considerable trouble at times to properly manipulate the same so as to secure uniformity 120 or regularity in the delivery from the carding cylinder to the doffer-rolls or cylinders.

In the employment of doffer-rolls such as 125 have hitherto been employed with leather bands having staples inserted therethrough to form the clothing thereof in the introduction of heat into the interior of the cylinder, it has been found in attempts made in that direction, that such deleteriously affected the leather, that is, caused the same to warp, as 130 well as destroyed the position and efficiency of the staples or clothing of such leather bands. Moreover, the warping of such leather bands applied to the rolls or cylinders super-

induced undue clogging of extraneous matter around and about the staples thereof and to overcome which has been a desideratum for a long time and a dilemma which has been regarded as unsurmountable, because means have not proven in the past to be at hand to overcome successfully the same or accomplish the desired results, until a doffer-roll or cylinder constructed according to my invention was designed and employed, because practice has fully demonstrated that the above mentioned objectionable features are entirely overcome thereby, and so that such fibrous materials as hereinbefore described can be treated with the employment of such doffer-rolls or cylinder under any and all conditions or changes of temperature with a resultant superior product by such treatment, and with thereby a great saving of the accumulating waste made, moreover, with a saving of time and labor of stopping the machine to strip the doffer-rings of the rolls or cylinders, because such rings are self strippers in this respect, that the fibrous material by reason of the arrangement of the teeth in staggered position in close parallel courses in contradistinction to being arranged in spiral courses, will not adhere thereto and after a long interval of time in the treatment of the material and stopping of the machine, it will be observed that the series of teeth in parallel courses of the rings due to the manner of arranging the same as hereinbefore described and securing them to the rings comprising the doffer rolls or cylinders, are maintained entirely free from any matter whatsoever, which is a result not heretofore regarded as possible or obtainable.

Among the advantageous features incident to the use of a doffer-roll or cylinder such as hereinbefore described, may be mentioned first, that the fleece or fibrous material treated thereby is thoroughly combed or straightened out and stripped of extraneous matter before being presented to the rubber-rolls or aprons for forming the same into sliver; second, by reason of the arrangement of the saw-toothed fillets or strips securely in the parallel grooves of the series of rings integrally applied to the roll or cylinder C, in contradistinction to the fillets or strips being spirally disposed thereon and with the respective teeth thereof occupying staggered positions with respect to each other, is due the superior results obtained of the thorough combing out of the material undergoing treatment thereby and the utter lack of adherence of extraneous matter thereto, because practice has demonstrated that they do not become clogged with such matter or with the fleece or fibrous material undergoing treatment; hence stopping of the machine is entirely avoided and the fleece or fibrous material combed or straightened out into parallel threads or courses thereby, is appreciably enhanced and commands a higher figure as an article; third, greater uniformity in the working of the ma-

terial is effected and a far better resultant product by the treatment is obtained, and fourth, owing to the solid character of the saw-toothed rings there is an entire absence of any tendency of the same to warp or to work loose on the roll or cylinder; and moreover, these doffer-rolls or cylinders can be set closer to the carding cylinder, thereby insuring more perfect clearance for the stock or other matter delivered therefrom and thus to enable the carding cylinder to present a superior quality or character of material for the complete or thorough straightening, combing out or cleaning by the doffer rolls and anterior to the presentation of the same to the rubber-rolls or aprons for transforming the fibrous or fleecy material into sliver, skeins or ribbons preparatory to the spinning thereof for subsequent uses in the arts.

Having thus described the nature and objects of my invention, what I claim as new, and desire to secure by Letters Patent, is—

1. In a carding machine, a doffer-roll, comprising a roll or cylinder having parallel groups of grooves and intervening smooth surfaced spaces between the groups and a series of saw-toothed metal strips secured into said groups of grooves to form rings, substantially as and for the purposes set forth.

2. In a carding machine, a doffer-roll, comprising a roll or cylinder having parallel groups of saw-toothed strips or fillets constituting integral rings, smooth surfaced spaces between the groups of integral rings and the teeth of each ring flaring and staggered with respect to the others of the roll or cylinder, substantially as and for the purposes set forth.

3. In a carding-machine, a doffer-roll comprising a hollow-cylinder having a coil of pipe mounted therein and having integral saw-toothed metal strips or fillets arranged in parallel courses in grooves thereof and forming rings disposed at suitable distances apart around and along the periphery of said cylinder, substantially as and for the purposes set forth.

4. In a carding-machine, a roll or cylinder provided with integral saw-toothed metal fillets or strips arranged in close parallel groups of grooves forming rings and smooth surfaced spaces between the groups of saw-toothed rings of the series constituting the doffer-roll or cylinder, substantially as and for the purposes set forth.

5. The method of forming a doffer-roll for a carding machine, which consists in forming in the body of the roll or cylinder closely arranged grooves in groups and in parallel courses to the ends of the roll or cylinder, cutting saw teeth in one edge of a metal strip or fillet, shaping or flaring the teeth and inserting into the groups of parallel grooves to form rings and intervening smooth or plain surfaced spaces between each of the groups of saw-toothed rings constituting the roll or cylinder and calking or securing the toothed strips or fillets to position in each of the

groups of grooves or recesses comprising a ring of the series of the roll or cylinder, substantially as and for the purposes set forth.

6. The method of forming a doffer roll or cylinder, which consists in forming grooves in the body of the roll or cylinder in groups and in parallel courses and smooth or plain surfaced spaces between each of the groups of grooves, forming on the edge of a strip or fillet of metal saw-teeth and presenting under pressure the toothed strip or fillet to each of the groups of grooves and inserting the same into said grooves to form saw-toothed rings and rigidly securing the same in said grooves with the respective teeth in parallel courses in each ring staggered with respect to the others thereof, substantially as and for the purposes set forth.

7. A doffer-roll for a condenser or finisher carding machine, comprising a cylinder with parallel groups of grooves formed in the body thereof and with saw-toothed metal strips or fillets suitably secured into said parallel groups of grooves to form rings, so that the

teeth thereof occupy staggered positions with respect to each other, smooth surfaced spaces between each of the groups of rings and means for securing said saw-toothed metal strips or fillets to position in said parallel groups of grooves, substantially as and for the purposes set forth.

8. A doffer-roll, comprising a hollow cylinder having a detachable steam coil or pipe supported to position therein and extending through the end journals thereof and saw-toothed rings seated into the body of said cylinder and the teeth of the same arranged to form a break joint or staggered position with respect to each other in parallel courses, substantially as and for the purposes set forth.

In testimony whereof I have hereunto set my signature in the presence of two subscribing witnesses.
